Des. 664

John F. Allen & Joseph Stewart, of
Philadelphia, Pa. Assignors to
J. G. Abbott & Lawrence, of Philadelphia, aforesaid
Letters Patent No. 664. Dated Aug. 8th 1854.

The schedule referred to in these Letters Patent and making part of the same.

To all whom it may concern:

Be it known, that we, John F. Allen and Joseph Stewart, of the city and County of Philadelphia, and State of Pennsylvania, have produced a new and original

Design for Franklin Stove.

and we do hereby declare that the following is a full, clear, and exact description of the same; reference being had to the annexed drawing forming part of this specification, in which

Figure 1 is a front elevation of the stove.

Figure 2 is a top view of the same, showing top and base plates.

Figure 3 is a front elevation of the foot.

The design being symmetrical but one half of the detail is given. Similar letters in the several figures denote the same part of the stove and design.

The front plate A bears on each side of the grate, a reeded semi-column B, arranged and configured as set forth in the drawing. Above the semi-columns B are the ornaments in bas-relief C, made up of the foliage a, and fruit b, arranged and having the configuration set forth in figure 1.

Above the grate is the tablet D, bearing the inscription, "Abbott & Lawrence Phila." in raised capitals; while from the tablet issues the foliage f, the arrangement and configuration being as set forth in figure 1.

The front plate A is surmounted by the moulding E, made up as shown in figure 1, and bearing the inscription "Patented 1854." in raised capitals and numerals.

The grate bars form the overlapping gothic arches F. G. while above the horizontal bar H, are the ornaments d and e; the design, con-

figuration and arrangement being as set forth in figure 1.

The top plate T is surrounded by a moulding J, made up as shown by section J taken on line x x of figure 2. At each end of the top plate is an ornament in bas-relief K, made up of leaves h, and fruit g, configured and arranged as set forth in figure 2.

The middle of the plate rises towards the pipe hole L, which is surrounded by... foliage P in bas-relief, as shown in figure 2; the stem l of the portion not shown running towards the front of the stove, and giving the appearance to the pipe hole of being encircled with foliage. In each corner of the middle portion of the top plate is the ornament m in bas-relief. The precise configuration and arrangement of the several ornaments on the top plate are as set forth in figure 2.

The base plate R is surrounded by a scroll moulding S and bears in front the ornament T in bas-relief, consisting of fruit and foliage arranged and configured as set forth in figure 2.

Upon the base plate is the plate W, raised above the base plate by the moulding V, shown by section V taken on line y y of figure 2. This plate inclines inward towards the base plate, and is ornamented with the ribbed and waving figure X, configured as set forth in figure 2.

The foot U has the outline shown by section on line m m, and is ornamented in bas-relief by the swells n n and foliage g, the arrangement and configuration being as set forth in figure 2.

What we claim as our production and desire to secure by Letters Patent, is — The design, configuration, and arrangement of the several ornaments in bas-relief, and mouldings, on the plates and foot of the stove, as set forth in this specification and annexed drawings.

In testimony whereof we have hereunto signed our names before two subscribing witnesses
